Inventor.
Wm. H. Hope.

UNITED STATES PATENT OFFICE.

WM. H. HOPE, OF WASHINGTON, DISTRICT OF COLUMBIA, ASSIGNOR TO THOMAS B. FLORENCE, OF PHILADELPHIA, PENNSYLVANIA.

MACHINE FOR SWEEPING STREETS.

Specification of Letters Patent No. 31,762, dated March 19, 1861.

To all whom it may concern:

Be it known that I, WM. H. HOPE, of Washington, in the District of Columbia, have invented a new and Improved Mode 5 of Cleaning or Sweeping Streets; and I do hereby declare that the following is a full and exact description thereof, reference being had to the accompanying drawings and to the letters of reference marked thereon.

10 The nature of my invention consists in the arrangement of a cylindrical brush revolving in a metallic, or other adjustable casing, whereby the dirt is gathered from the streets, lanes, or alleys, and thrown into 15 the close box or body of the machine, that can be carried off and emptied at some convenient place when a full load is collected.

It also consists in the arrangement of lever L, in combination with the axle A, 20 bar R and connecting rods r r, whereby the brush is thrown out of gear when it is necessary to remove the machine to some distant place to empty its load.

25 In the drawings Figure 1 shows a perspective view of the machine. Fig. 2 a top view and Fig. 3 a side view.

To enable others skilled in the art to make and use my invention I will proceed to describe its construction and operation.

30 W W' show the large wheels on which rest the body and other parts of the machine.

C C are the cogs on wheel W in which the cogs of small cog wheel w mesh, or work, for 35 the purpose of driving the brush B, said brush B being made of cylindrical form, of hickory splits, or other similar material, and revolves in casing a a, which casing a a is made adjustable so as to be placed up to the 40 brush B as said brush wears away. This casing a a encircles about one-half the brush, commencing near, or on the ground and ending at the top center of brush B; the object of this casing is to enable the brush B 45 to convey the dirt, or sweepings, into the box b or body of the machine.

i i', show the places where the adjustable casing is attached to the body of the machine.

50 i'' i'' is an adjustable partition, which is made to work to the brush B and separates the dirt, or contents, of box or body b, (when said contents are collected from brush B).

b' is the movable bottom of box b which is to be removed when necessary to empty 55 the load.

A A show the axle, R the cross bar, to which lever L is attached, and r r rods which connect R and L with axle A. Lever L, cross bar R and rods r r are so connected 60 with box b and axle A A as to move box b when it is necessary to ungear the brush B.

s is the slot in box b in which axle A moves.

l shows a lever which the driver works 65 with his foot when necessary to raise the brush B from the ground, or lower the same.

t is the hinged top, or cover, which is used for keeping the dust confined when the machine is in operation and to enable the driver 70 to see the contents of the box b.

S is the driver's seat and s s the shafts.

r' r' are small ratchet bars used for the purpose of holding partition i'' i'' in place, partition i'' i'' being hinged or made mov- 75 able at its bottom.

w' w' are small wheels seen in front of the machine, intended to bear the brush from the ground and prevent it (the brush B) from bearing too hard on the ground, or 80 pavement. Said wheels may be made adjustable so as to be raised, or lowered, as the brush B wears away. The brush B is so arranged in its bearings that it can be turned end for end, when necessary, or easily taken 85 out for repair, &c.

h h are handles, to be used when it may be necessary to use the machine by man instead of horse power.

The principles of this machine may be 90 applied to a four wheeled two horse vehicle, or machine, as well as to such a one as is above described and shown in the drawings.

This machine differs from all other street sweeping machines, inasmuch as but a single 95 revolving brush, running in an adjustable half casing, is used to convey the dirt, immediately into a close box which is emptied from its bottom. Also in the mode of gearing and ungearing the brush and the combination and arrangement of other parts of the machine.

Therefore what I claim and desire to secure by Letters Patent is:

1. The arrangement of a cylindrical brush, 105 in street sweepers, revolving in a metallic,

or other, adjustable casing, as described, whereby dirt and other substances are gathered, without any other mode of conveyance, into the box or body of the machine, as set forth and described.

2. The arrangement of lever L in combination with bar R, connecting rods *r r* and

axle A, which are attached to box, or body, b for the purpose of ungearing brush B, as set forth and described.

WM. H. HOPE.
